UNITED STATES PATENT OFFICE.

ALRAH B. EDWARDS, OF CHICAGO, ILLINOIS, AND FRANK K. RUSSELL, OF DALLAS, TEXAS, ASSIGNEES TO SHORTWRITER COMPANY, OF WILMINGTON, DELAWARE, A CORPORATION OF DELAWARE.

WRITING-MACHINE.

1,224,085.

Specification of Letters Patent. Patented Apr. 24, 1917.

Application filed December 10, 1915. Serial No. 66,031.

To all whom it may concern:

Be it known that we, ALRAH B. EDWARDS and FRANK K. RUSSELL, citizens of the United States, residing, respectively, at Chicago, in the county of Cook and State of Illinois, and Dallas, in the county of Dallas and State of Texas, have jointly invented certain new and useful Improvements in Writing-Machines, of which the following 10 is a specification.

This invention relates to writing machines and has for its principal object the provision of novel and efficient mechanism to automatically cause the ribbon to reciprocate transversely of itself as the keys are successively actuated to make impressions therethrough, whereby the life of the ribbon is greatly prolonged.

A further object of my invention is the 20 provision of means to rotate the platen step by step at each actuation of one or more of the keys.

Further objects and advantages of my invention will be apparent as it is better understood by reference to the following 25 specification when read in connection with the accompanying drawing, disclosing the preferred embodiment thereof, in which—

Figure 1 is a top view of a stenographic 30 or short writing machine, a portion of the casing top being broken away to show parts therebeneath;

Fig. 2 is a vertical sectional view of the 35 machine taken upon the line X—X of Fig. 1;

Fig. 3 is a top view of the platen and correlated parts, and

Fig. 4 is an end elevation thereof with a portion of the frame in section.

Reference character 1 designates the platen which will preferably have the form of a roller fast upon a shaft 4 which is journaled in semi-circular open bearings 3 formed in the upper ends of a pair of standards 2. Slotted members 5 are slidably secured over the bearings by screws 5^a. When it is desired to remove the platen from the machine, the screws 5^a may be loosened and the members 5 slid clear of the 50 bearings 3. The shaft 4 carries a hand-knob 4^a on one end thereof. The frame carries a pair of projecting members or lugs 6, to which is pivotally secured a pair of ribbon carrying arms 9. I prefer to employ the

55 pivot bolts 7 carrying the nuts 8 for the purpose of forming the pivotal connections between these parts. The arms 9 are provided at the outer ends with the elongated slots 10 receiving the ribbon 11. The arms 9 are rigidly connected by a cross bar 12 which is 60 provided on its rear edge with teeth 13. The paper is fed around the platen 1 from a supply roll 13^a in the rear of the machine, and when it is desired to remove a portion 65 of the paper which has already been written on, it is torn off across the toothed bar 12.

To the shaft 4, adjacent one extremity of the platen 1, a circular cam 14 is eccentrically secured upon which rests a lug 15 depending from one of the arms 9. As the shaft 4 is rotated, the cam 14 causes the arms 9 to swing about the pivot bolts 7, whereby an up and down movement is communicated to the portion of the ribbon 11 between the 75 arms 9 adjacent to the platen.

A mechanism for communicating an intermittent rotation to the platen from a suitable keyboard will now be described. The keys comprising said keyboard are designated by the numeral 16, and are respectively mounted upon the forward extremities of key levers 17, pivoted at their rear ends upon a rod 18. Transversely above the middle portions of the key levers is mounted 85 a rod 19 upon which are pivoted type bars 20 of bell-crank form, each having an upwardly extending forwardly inclined arm carrying a type and a substantially horizontal rearwardly projecting arm which is 90 connected by a vertical link 21 with an underlying key lever 17. The ribbon 11 passes between the platen and the type carried by the upper extremities of the bars 20. Upon the rod 19 is also pivoted an upwardly 95 extending universal bar 22, the upper edge of which is engaged by a plurality of hooks 23, one of which extends forward from each bar 20. It is apparent from the description above given and from the drawings that 100 when any key 16 is struck, subjecting a certain key lever 17 to a downward angular displacement, the corresponding type bar will be subjected to a rearward angular displacement, to bring the type carried by said 105 bar into contact with the ribbon 11, pressing the latter against the paper passing over the platen. Owing to the hooks 23 the rearward

displacement of any type bar will subject the universal bar to a similar displacement and the last named bar will automatically return any type bar to its normal position owing to the tension of a coiled spring 24 (Fig. 2) extending forwardly and downwardly from the upper portion of the universal bar to a bracket member 25. Upon the top of the universal bar is pivotally mounted a bell-
 10 crank 26, the pivotal point being at the apex of the bell-crank. One arm of the member 26 is substantially vertical and is acted upon by a coiled spring 27, tending to produce a counter-clockwise angular displacement of the member. The other arm of the member 26 has the nature of a hooked pawl engaging a ratchet wheel 28 secured to the shaft 4 adjacent one extremity of the platen. Owing to the construction just described, after any
 15 20 key has been struck, the platen will be subjected to a clockwise rotation as the key is being returned to its normal position by the universal bar. Thus it will be seen that as the various keys of the machine are success-
 25 sively struck, the platen will be intermittently rotated and will automatically cause the portion of the ribbon between the arms 9 to gradually shift up and down. The vertical displacement to which the ribbon is
 30 subjected will be such that the type carried by the bars 20 may strike against the upper and lower portions of the ribbon according as the latter is in its lowered or raised position.
 35 It will of course be understood that the ribbon will also be intermittently fed in a direction parallel with the platen while the machine is being used, but no description of the mechanism accomplishing this result is
 40 essential herein since it has no direct relation with the invention herein set forth.

The invention is presented as including all such changes and modifications as come within the scope of the following claims.

45 I claim:

1. In a writing machine, the combination of a frame, a platen rotatably mounted thereon, ribbon spools rotatably mounted on said frame in normally fixed relation thereto, and means engaging the ribbon between said spools and actuated by the rotation of said platen to automatically impart lateral movement to the portion of the ribbon between said engaging means.
- 55 2. In a writing machine, the combination of a frame, a platen rotatably mounted thereon, ribbon spools rotatably mounted on said frame in normally fixed relation thereto, pivoted arms having means thereon to engage the ribbon between said spools, and means operable when said platen is rotated to automatically actuate said arms to impart a lateral movement to the portion of the ribbon between said arms.
- 65 3. In a writing machine, the combination

of a frame, a platen rotatably mounted thereon, ribbon spools rotatably mounted on said frame in normally fixed relation thereto, means engaging the ribbon between said spools and actuated by the rotation of 70 said platen to automatically impart a lateral movement to the portion of the ribbon between said engaging means, and key-actuated means to rotate said platen.

4. In a writing machine, the combination 75 of a frame, a platen rotatably mounted thereon, ribbon spools rotatably mounted on said frame in normally fixed relation thereto, pivoted arms having means thereon to engage the ribbon between said spools, 80 means operable when said platen is rotated to automatically actuate said arms to impart a lateral movement to the portion of the ribbon between said arms, type bars mounted adjacent the platen, keys connected to said 85 type bars, and an operative connection between said keys and platen, whereby when one of the former is actuated the latter is caused to rotate.

5. In a writing machine, the combination 90 of a frame, a platen rotatably mounted thereon, ribbon spools rotatably mounted on said frame in normally fixed relation thereto, pivoted arms having means thereon to engage the ribbon between said spools, a 95 cam operable when said platen is rotated to automatically actuate said arms to impart a lateral movement to the portion of said ribbon between said arms, a plurality of type bars pivoted adjacent said platen, a member 100 arranged to swing, a connection between each type bar and said member, and co-operating means on said platen and member whereby the former is rotated when either of said type bars is actuated.

6. In a writing machine, the combination 105 of a bed, a platen, rotatable spools mounted in normally fixed relation to the bed, type bars mounted adjacent the platen, a ribbon carried by the spools and traversing between 110 the platen and the type bars, ribbon supports at each end of the platen between said spools, and means operated by the platen for swinging the ribbon supports independently of the spools.

7. In a writing machine, the combination 115 of a bed, a platen, rotatable spools mounted in normally fixed relation to the bed, type bars mounted adjacent the platen, a ribbon carried by the spools and traversing between 120 the platen and the type bars, ribbon supports at each end of the platen between said spools, means operated by the platen for swinging the ribbon supports independently of the spools, and key-actuated means for 125 imparting rotation to the platen.

8. In a writing machine, the combination 130 with a platen, a ribbon, and means automatically operated by the platen for shifting the ribbon sidewise, of a plurality of type

bars pivoted adjacent the platen, a member arranged to swing, a connection between each type bar and the member, and means mounted on the member for imparting rotation to the platen.

9. In a writing machine, the combination with a platen having a ratchet at one end, and a ribbon traversing longitudinally of the platen, of a plurality of pivoted type bars, a hook projecting from each type bar, a swinging bar engaged by each hook, a support, a coiled spring extending from the support to the swinging bar, a bell-crank

lever pivoted on the swinging bar and having its long arm engaging the ratchet of the platen, a second support, and a coiled spring extending from the second support to the short arm of the bell-crank lever.
